(57) **CLAIM**

The ornamental design for a height adjustable lamp holder, as shown and described.

DESCRIPTION

FIG. 1 is a perspective view of a height adjustable lamp holder showing my design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

The broken lines in the drawings illustrate portions of the height adjustable lamp holder and form no part of the claimed design.

1 Claim, 6 Drawing Sheets

FIG. 1

FIG. 2

FIG. 3

FIG. 4

FIG. 6

FIG. 7
